(57) **CLAIM**

The ornamental design for a fan case, as shown and described.

DESCRIPTION

FIG. 1 is a perspective view of a fan case showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partial enlarged view of FIG. 1; and,

FIG. 10 is a partial enlarged view of FIG. 2.

The portions shown in light gray illustrate portions of the fan case that form no part of the claimed design.

1 Claim, 8 Drawing Sheets
